CLAIM

The ornamental design for a combined distractor and compressor medical instrument, as shown and described.

DESCRIPTION

FIG. 1 is a front perspective view of a combined distractor and compressor medical instrument showing our new design, in the distractor position;

FIG. 2 is a top plan view thereof;

FIG. 3 is a bottom plan view thereof;

FIG. 4 is a front elevation view thereof;

FIG. 5 is a left side elevation view thereof;

FIG. 6 is a right side elevation view thereof;

FIG. 7 is a back elevation view thereof;

FIG. 8 is a front elevation thereof with a part shown in as alternate position;

FIG. 9 is a front perspective view of the combined distractor and compressor medical instrument, in the compressor position;

FIG. 10 is a top plan view of FIG. 9;

FIG. 11 is a bottom plan view of FIG. 9;

FIG. 12 is a front elevation view thereof with parts shown in the positions shown in FIG. 9; and

FIG. 13 is a left side elevation view of FIG. 9;

FIG. 14 is a rear elevation view of FIG. 9; and,

FIG. 15 is a right side elevation view thereof.

The broken line showing of the combined distractor and compressor medical instrument is for illustrative purposes only and forms no part of the claimed design.
